OVERFEED STOKER

Joseph J. Durand, Minneapolis, Minn.

Application July 16, 1935, Serial No. 31,661

5 Claims. (Cl. 110—101)

This invention relates to overfeed types of stokers.

The primary feature of the present invention is to provide a construction that utilizes a movable pedestal for supporting the weight of the stoker and uses the pedestal as a conductor for supplying air under the grate of the furnace.

Further objects of the invention are to provide fixed air supplies that control the ratio of the volume of air fed under the grate to air fed over the grate in the proportion of 9 to 1; that minimizes the leakage of air into the furnace by a design that admits tight joints; that allows withdrawal and insertion of the stoker with ease and dispatch permitting easy servicing, repairing and inspection; that is strong, compact and durable; and that is comparatively inexpensive to manufacture and operate.

With the foregoing and other objects in view the invention consists of a novel construction, combination and arrangement of parts as will be hereinafter more specifically described and illustrated in the accompanying drawings wherein is disclosed an embodiment of the invention, but it is to be understood that changes, variations and modifications may be resorted to without departing from the spirit of the claims hereunto appended.

In the drawings wherein like reference characters denote corresponding parts throughout the several views:

Figure 1 is a side elevation of a furnace in a dotted line skeleton view illustrating an adaptation therewith of a stoker in accordance with the present invention.

Figure 2 is an enlarged fragmentary detailed vertical section through a portion of the stoker.

Figure 3 is a horizontal section taken substantially on line 3—3 of Figure 1 and looking in the direction of the arrows.

Figure 4 is a plan view of the gasket for the joint between the spout and the bowl.

Figure 5 is a fragmentary elevation through a portion of the platform with parts removed.

Figure 6 is a rear elevation of the assembled spout flange and the flange removed from the spout.

Referring to the drawings in detail, A indicates a furnace having a grate 5 dividing the furnace into the firebox 6 and ash pit 7. The opening for the firebox is indicated at 8 and the ash pit door is indicated at 9. Throughout the description, "rear" is used to indicate a direction toward the left of the drawings.

As is customary in installing overfeed stokers

the firebox door is removed and in its place is substituted a plate 10 that may be secured to the furnace wall in any conventional manner. In this plate there is an opening 11 through which extends the spout of the stoker as will hereafter appear.

It is to be understood that the features of the present invention apply to the overfeed type stoker wherein the coal is fed to the fire on the grate 5 from a point above the fire which latter is indicated at 12. The stoker includes a bowl member indicated generally at 14 which is made with a bottom wall 16 having a central opening. In the form of the invention illustrated this bowl is preferably rectangular in configuration. Rising from the bottom wall are a pair of spaced side walls 16a, and an apertured front end wall 19a, and a rear end wall 19, the latter having a pair of openings 20a and 20b one over the other. The top of the bowl is open, and around the opening is a lip 13a which receives the neck of the coal storage hopper 13. The interior of the bowl 14 is divided transversely by the horizontal wall 26 which divides the space between the side walls 16a into a coal pocket 30a and an air chamber 31. The power driven ram 30 reciprocates in the coal pocket and forces coal forwardly into the spout indicated generally at 20.

Secured to the rear flange 16b of the bottom wall 16 of the bowl in any suitable manner as by bolts 16c is a rearwardly extending horizontal platform 15. On the platform is mounted a fan casing 17 housing a power driven fan (not shown) which casing has a neck extending through the lower opening 20a in the rear wall 19 of the bowl. The fan supplies air under predetermined pressures to the chamber 31. The power driven ram 30 extends through the upper opening 20b. The ram and fan are driven by suitable transmission mechanism obvious to skilled persons from an electric motor (not shown) and the platform 15 furnishes a support for the transmission mechanism and motor. On the platform to the rear thereof is mounted the electrical control box 18 which houses the customary electrical control switch for operating the parts of the stoker.

The spout 20 is an elongated hollow member oval in cross section and is made in upper and lower companion sections 21 and 22 which when coupled together form a coal chute 21a in the upper part and an air passage 32 in the lower part which latter discharges air at the forward end through openings 33 over the grate 5. The lower section 22 has a top wall 27 which divides the interior of the spout and aligns with wall 26 to

form a track for the ram 30 and a floor for the chute by which coal from the hopper 13 is intermittently forced through the chute 21a into the fire box 6 of the furnace through opening 34 in the forward end of the upper section 21.

The spout 20 is mounted on the bowl and supported thereby to extend forwardly in a horizontal position. For this purpose there is a ring flange 23 on the rear end of upper section 21 bolted to the forward wall 19a of the bowl and this ring flange extends about the opening in the forward wall. The lower section 22 has a semi-circular flange 24 bolted against the lower segment of the ring flange 23. Between the flange 23 and the wall 19a is held an asbestos gasket 25 having an orifice 25a of fixed area therein which forms a communication between the air chamber 31 and the passage 32 below the walls 26 and 27. Air from the fan casing is transmitted through the orifice 25a into the passage 32 and is fed over the grate 5. There is also a gasket 25b between the flange 23 and the flange 24. The gaskets 25 and 25b form an air tight joint between the sections of the spout 20 and the bowl 14. The amount of air passing through the passage 32 is controlled by the size of the orifice 25a which is designed to admit one part air to pass over the grate to five parts of air fed under the grate. The spout 20 extends through the opening 11 in plate 10 that has been substituted for the door of the furnace. The spout may be moved into and out of the firebox of the furnace with ease and dispatch so as to permit inspection and repairs by reason of the air seal flange 35 embracing the spout. This flange is formed in two companion sections 35a and 35b, the one section 35b having an extension lug 35c at each end overlapping the ends of the companion section 35a as will be understood from Figure 6 of the drawings. The sections are secured in embracing relation about the spout 20 by means of a bolt 36, the shank of which extends through openings in upper section 21 bridging the chute above the partition wall 27 so as not to interfere with the progress of the coal through the chute. About the forward face of flange 35 there is a ring groove 37a in which is seated an asbestos ring 37 that bears against the outer face of plate 10 and forms an air tight seal between the flange and the plate when the spout is in operative position within the furnace.

Some types of stokers are designed to carry the weight of the parts as well as the weight of the coal in the hopper laterally of the standard or support C on which the stoker swings into and out of operative relation with the furnace. I still retain the standard or support C upon which the parts swing but I design a pedestal B to be located beneath the weight of the parts, utilize this pedestal for conveying the air supply to the ashpit of the furnace and place a caster wheel on the bottom of the pedestal to impart more efficient mobility to the stoker all of which promotes a balanced distribution of weight in my improved stoker.

The standard or support C consists of a foot plate 70 anchored to the floor 58 by means of foundation bolts 71. From the foot plate 70 rises a spindle 72 which terminates below the bowl casting 14. A horizontal laterally extending arm 73 has a sleeve 74 on its inner end rotatably mounted on the spindle 72 and this arm in certain types of stokers carries all of the weight of the parts of the stokers which weight is distributed laterally of the spindle 72. On the outer end of

arm 73 there is a sleeve bearing 75 which is rotatably mounted on a sleeve 38. The interior of the sleeve communicates with air chamber 31 through the bottom wall 16 of the bowl casting 14. The sleeve 38 forms a part of pedestal B.

The mobile pedestal B further includes the vertical under-air conductor pipe 43 having the upper end extending through sleeve 38 and communicating with air chamber 31. On an intermediate portion of the air conductor pipe 43 is a collar 44 having an outset annular shoulder 44a on its upper end. To make an air tight seal there is a sleeve shim 46 disposed between sleeve 38 and conductor pipe 43. The lower ends of the shim 46 and sleeve 38 seat in the pocket of the outset shoulder 44a and the lower end of bearing sleeve 75 bears on the upper end of said shoulder 44a. Set screws 45 anchor the collar to the conductor 43 and set screws 45a anchor the outset shoulder 44a to the sleeve 38.

The mobile pedestal B further includes at its bottom an elbow casting formed with a tubular vertical leg 39 and a tubular horizontal leg 40 and the wall of the horizontal leg 40 about the mouth of the open outer end thereof is flared at 41. The upper end of the vertical leg 39 of the elbow has a counter-bore 42 in which the lower end of the conductor pipe 43 is seated. The arrangement of the elbow and conductor pipe 43 forms a passage 47 which communicates at 30 its upper end with chamber 31 and a part of the air from the fan casing 17 passes downwardly while the remaining portion passes forwardly through the air passage 32. The size of the passage 47 with respect to orifice 25a forming the entrance to chamber 32 is such that the volume of air passing under the furnace grate is in the proportion of nine to one of the volume of air passing into the furnace over the grate.

For conducting the air under the grate from passage 47 into the ash pit 7 of the furnace there is a flexible metallic pipe 77 having fixed by means of rivets or the like to one end thereof a tapering bushing 48 that seats in the tapered mouth 41. On the ashpit door 9 is secured a flanged collar 49 having a tapered bore internally thereof which meshes with a like tapering opening 50 in the door 9. The tapered bore in the flange collar and the opening 50 form a continuous seat for a tapering bushing 51 slidably yet snugly fitting on an outer portion of the flexible pipe 77. Embracing the intermediate portion of the flexible pipe 77 is a coil spring 52 one end of which maintains the movable bushing 51 in seated relation in the bore of the collar and opening 50 while the other end of the spring bears against the bushing 48. The latter construction forms an air tight seal between the elbow and the ashpit of the furnace for conducting air from the passage 47 in the pedestal B into the ashpit of the furnace. So that the pedestal may be moved with ease and dispatch for assembling and removing the stoker from the furnace there is bolted as at 53 a plate 54 to which is swiveled a caster wheel 56. The caster wheel rides on a segmental-shaped track 57 and this track is imbedded in the floor 58. By reason of this construction the pedestal may be moved freely about standard C while it is supporting substantially the entire weight of the stoker which movement allows the spout 20 to be withdrawn from the firebox and permits the gland 51 and the flexible conductor pipe 77 to be withdrawn from the door 9 to allow repairs and inspection to the furnace.

When in operating position, additional support 75

is supplied to the stoker by means of a swinging leg formed of two aligned sections 59 and 60. The upper end of leg section 60 is pivoted on a pin 62 which is secured to depending portions of 5 a pair of spaced plates 78 bolted as at 79 to the opposite sides of the platform 15. The lower end of leg section 59 has a foot piece 63 that is adapted to engage with the floor 58. The confronting ends of the leg sections are connected 10 together by a turn buckle sleeve 61. When it is desired to move the stoker away from the furnace, turn buckle sleeve 61 may be rotated so as to withdraw leg section 59 from the floor and permit it to be swung into dotted line position shown 15 in Figure 1 of the drawings. When the stoker is assembled, however, the angle indicated by the arrows at 65 should be slightly greater than a right angle so that the weight of a stoker is urged forwardly making a tight fit between the 20 plate 10 and the flange 35 on the spout 20.

So as to provide additional bracing for the stoker there is a metal strap brace 66 having one end secured as at 67 to a side wall of the bowl 14 and the rear end secured as at 68 to the 25 trol box. There is one brace 66 on each side of the stoker.

Having thus described the invention, what is claimed as new is:

1. The combination with a furnace including a 30 fire box provided with a grate, of a stoker including a bowl having an air chamber and a coal pocket, a spout secured to the bowl and extending into the fire box above the grate, said spout having a coal chute registering with the coal 35 pocket and a conductor registering with the air chamber at one end and with the fire box at the other end to feed air over the grate, a hollow pedestal arranged to support the stoker and equipped with a passage communicating with 40 said air chamber, a flexible air conductor communicating at one end with the passage in the pedestal and at the other end with the furnace under the grate, and bushing fittings between the ends of the flexible conductor and the pedestal and the furnace respectively.

2. The combination with a furnace including a 45 fire box provided with a grate, of a stoker including a bowl having an air chamber and a coal pocket, a spout secured to the bowl and extending into the fire box above the grate, said spout having a coal chute registering with the coal 50 pocket and a conductor registering with the air chamber at one end and with the fire box at the other end to feed air over the grate, a hollow pedestal arranged to support the stoker and equipped with a passage communicating with 55 said air chamber, a flexible air conductor communicating at one end with the passage in the pedestal and at the other end with the furnace under the grate and bushing fittings between the ends of the flexible conductor and the pedestal and the furnace respectively, and spring means 60 embracing the flexible conductor for urging one of the fittings into connection with the furnace under pressure.

3. The combination with a furnace including a

fire box provided with a grate, of a stoker including a bowl having an air chamber and a coal pocket, a spout secured to the bowl and extending into the fire box above the grate, said spout having a coal chute registering with the coal 5 pocket and a conductor registering with the air chamber at one end and with the fire box at the other end to feed air over the grate, a hollow pedestal arranged to support the stoker and equipped with a passage communicating with 10 said air chamber, a flexible air conductor communicating at one end with the passage in the pedestal and at the other end with the furnace under the grate, and bushing fittings between the ends of the flexible conductor and the pedestal 15 and the furnace respectively, spring means embracing the flexible conductor for urging one of the fittings into connection with the furnace under pressure, and said pedestal being swingable.

4. The combination with a furnace including a fire box provided with a grate, of a stoker including a bowl having an air chamber and a coal pocket, a spout secured to the bowl and extending into the fire box above the grate, said spout having a coal chute registering with the coal pocket 20 and a conductor registering with the air chamber at one end and with the fire box at the other end to feed air over the grate, a hollow pedestal arranged to support the stoker and equipped with a passage communicating with said air chamber, a 30 flexible air conductor communicating at one end with the passage in the pedestal and at the other end with the furnace under the grate, bushing fittings between the ends of the flexible conductor and the pedestal and the furnace respectively, 35 spring means embracing the flexible conductor for urging one of the fittings into connection with the furnace under pressure, said pedestal being swingable, and an adjustable auxiliary leg swingably connected at its upper end to the stoker and 40 adapted for engaging the floor at its lower end.

5. In an overfeed stoker, the combination of a bowl comprising a coal receiving chamber and an air chamber, a pedestal on which said bowl is mounted, a hopper mounted on the bowl in communication with said coal receiving chamber, a platform extending rearward from the bowl, a power driven fan carried by the platform and arranged to deliver air to said air chamber, a power driven coal feeding ram extending into said coal receiving chamber, a spout extending forwardly from the bowl, including a chute communicating with said coal receiving chamber and an air passage communicating with said air chamber, said chute and air passage being adapted to discharge into 55 a furnace, a supporting leg swingably secured at its upper end to the platform and adapted to rest at its lower end on the floor, a collar slidably adjustable on the spout, said pedestal being hollow and having its interior communicating with said 60 air chamber, and a flexible air conductor communicating at one end with the interior of the pedestal and having its other end adapted to communicate with a furnace beneath a grate therein. 65

JOSEPH J. DURAND.
